UNITED STATES PATENT OFFICE.

WALTER ERNI, OF MILWAUKEE, WISCONSIN.

DRIVING MECHANISM FOR WASHING MACHINES.

1,422,843.

Specification of Letters Patent. Patented July 18, 1922.

Application filed June 25, 1917. Serial No. 176,743.

To all whom it may concern:

Be it known that I, WALTER ERNI, a citizen of the United States, residing at Milwaukee, county of Milwaukee, and State of Wisconsin, have invented new and useful Improvements in Driving Mechanism for Washing Machines, of which the following is a specification.

My invention relates to improvements in 10 washing machines.

The object of my invention is to provide improved means for utilizing the power of a small motor to impart reciprocating motion to a washing drum. Also to provide means 15 for readily disengaging the power transmitting connections from the drum without stopping the motor, and reengaging the same at pleasure while the motor is running. A further object of my invention is 20 to provide means whereby the movements of the drum may be reversed without shock to the motor and power transmitting connections.

In the drawings:

25 Figure 1 is an end elevation of a washing machine, embodying my invention.

Figure 2 is a fragmentary view of the same in side elevation.

Like parts are identified by the same reference characters throughout the several views.

The frame includes a set of legs 1 at each end which converge and support a bearing member 2, in which trunnions 3 projecting 35 axially from an oscillatory drum 4 are mounted. The drum 4 is an ordinary washing drum provided with a hinged lid or door 5 affording access to the interior of the drum for the insertion and removal of clothes.

40 The frame is provided with an upwardly projecting arm 10, preferably inclined as shown, and provided with a shelf 11 at its upper end to support a motor 12. The power of the motor is applied to the drum 45 through pinion 13 and a train of gears and pinions 14, 15, 16, 17 and 18, together with a connecting rod 19 pivotally secured to a crank 20 on gear wheel 18, and having its lower end pivotally connected with a sliding rack bar 21 having teeth 22 in mesh 50 with the teeth 23 of pinion 24 mounted upon trunnion 3.

The shaft 25 which carries gear wheel 18 preferably extends longitudinally from one 55 end of the machine to the other, and is sup-

ported at its respective ends by an arm 10 at each end of the machine, whereby the drum may be positively driven at both ends by gear wheel 18, connecting rod 19, rack bar 21 and pinion 24, as above described. 60 The desirability of driving the drum at both ends will depend largely on the size of the machine. For small machines it is sufficient to actuate the drum at one end only.

Rack bar 21 is mounted to slide upon a 65 swinging supporting member or lever 30, this lever being provided with a suitable projection 31 loosely engaged in a slot 32 in the rack bar and serving as a guide along which the rack bar 21 may be reciprocated. 70 In the position in which the parts are illustrated by full lines in Figure 1 the teeth 22 of the rack bar are in engagement with the teeth 23 of pinion 24, but the member 30 is adapted to be swung upon its pivotal connection with the frame at 35 to the dotted line position indicated in Figure 1, thereby withdrawing the rack bar from pinion 24 to disengage the power transmitting connections and allow the drum to come to rest 75 without stopping the motor 12. This adjustment of the swinging member 30 is derived from a manually operated lever 40 which transmits motion through rock shaft 41, arm 42, and link 43, the latter being pivoted to 80 the lower end of member 30 at 44, whereby when the lever 40 is swung to dotted line position the rack will be disengaged from pinion 24. Lever 40 is provided with a manually operable latch 45, whereby it may be 85 locked in either the drum actuating or drum releasing position. For the larger machines, shaft 41 will be extended from one end of the frame to the other and the lever and link connections duplicated at the opposite 90 end of the machine to swing the rack 21 into and out of pinion engaging position at that end simultaneously with the corresponding movements of the rack 21 at the end illustrated in Figure 1.

100 With the construction illustrated, it is obvious that with each complete revolution of gear wheel 18 rack 21 will be reciprocated in two directions, the rack moving downwardly during the first half turn of gear wheel 18 and upwardly during the last half turn when the gear is revolved in the direction indicated by the arrow in Figure 1. It is therefore obvious that the drum will be rotated in one direction during the first 105 110

half turn of said gear wheel 18, and in the other direction during the last half turn, the movement of the drum ceasing in each case when crank pin 20 approaches the so-called "dead center line." Owing to the fact that the movement of the drum is reversed when the crank crosses the "dead center line" it is obvious that the reversal will take place without shock to the driving mechanism since the drum will be slowly brought to rest as the crank approaches the center line, and its movement in the opposite direction will be slowly started as soon as the crank crosses said line.

10 15 I claim:

Driving mechanism for washing machines having an oscillatory drum, said driving mechanism comprising a pinion operatively connected with said drum, an oscil-

latory rack adapted to be thrown into and 20 out of mesh with said pinion, a guide for said rack pivotally mounted to swing about a point above said pinion, means for reciprocating said rack, a bell crank lever linked to the lower end of said guide for 25 moving said rack into and out of mesh with said pinion, said bell crank lever having a substantially vertically disposed manually operable arm, and means carried by said arm for positively locking said arm in 30 either of its two extreme positions.

In testimony whereof I affix my signature in the presence of two witnesses.

WALTER ERNI.
